HAIR CURLING DEVICE

Naomi G. Morton, New York, N. Y.

Application January 14, 1944, Serial No. 518,211

7 Claims. (Cl. 132—40)

This invention relates to a new and improved hair curling device. The principal object thereof is to provide a pliable hair curling device, which can be manipulated and used with great facility.

Another object of the invention is to provide a new and improved flexible hair curler which is compact and which is not cumbersome.

Another object of the invention is to provide a hair curling device which is simple in construction and handy to use.

Another object of the invention is to provide an adjustable hair curler, adjustable in the sense that it can readily be adapted to accommodate strands of hair of varying thicknesses.

Still another object of the invention is to provide a pliable hair curling device which can be left in the hair overnight without any discomfort to the user while asleep or reclining.

Numerous additional objects of the invention are stated in the annexed description and drawing which illustrate preferred embodiments thereof.

Fig. 1 is a perspective view of the first embodiment.

Fig. 2 is a sectional view on the line 2—2 of Fig. 1.

Fig. 3 is a sectional view on the line 3—3 of Fig. 2.

Fig. 4 is a sectional view on the line 4—4 of Fig. 2.

Fig. 5 is a perspective view of the curling device, showing portions of the top disc member bent downwardly to hold the spirally wound lock of hair.

Fig. 6 is a top plan view of the second embodiment.

Fig. 7 is a sectional view on the line 7—7 of Fig. 6.

Referring to the first embodiment (Figs. 1 to 5), the device comprises a pair of spaced and axially aligned pliable disc members 10 and 11, which are connected to each other by the flexible twistable strip member 15. The said disc members are similarly shaped and are of the same size. Member 10 is the top or upper disc, and member 11 is the bottom or lower disc. The said disc members can be made of leather, paper, metal foil or any suitable flexible and pliable material.

As shown in Figs. 2 and 3, top disc member 10 is reinforced by a number of intersecting short lengths of flexible copper wire 13 located at the bottom face thereof. The said wires are held to the bottom face of disc member 10 by a

10 facing or covering 12 which is secured to the underside of disc 10 in any desired manner. Said facing 12 may be made of fabric or any similar material and is substantially of the same size, shape and contour as disc member 10. The top surface of lower disc member 11 is also covered by a fabric facing or covering 14 which can be connected or adhered thereto in any suitable manner. Said facing 14 is identical in configuration and size with disc member 11. Disc member 10 and its facing 12 will hereinafter be referred to as the upper disc member, and disc member 11 and its facing 14 will hereinafter be referred to as the lower disc member.

15 As shown in Figs. 2 and 3, upper disc member 10 is provided with a pair of small, substantially centrally located and aligned openings 16 and 16a. Lower disc member 11 is provided with a small opening 18a and the radial slot 18, said slot terminating in the periphery of disc 11. When disc members 10 and 11 are in the axially aligned position shown in Fig. 2, opening 16a in disc 10 is aligned with opening 18a in disc 11 and opening 16 in disc 10 is aligned with the closed end of slot 18 in disc 11.

20 The two disc members 10 and 11 are connected to each other by means of a twistable continuous connecting strip 15. The said strip 15 comprises the end portions 15c and the intermediate vertical arms 15a and the base portion 15b, all of which are integral and in a single continuous strip. The vertical arms 15a and the base 15b form a U-shaped member upon which the lock of hair is spirally wound.

25 End portions 15c of the connecting strip 15 are secured to the top face of upper disc member 10 in any suitable manner. Strip 15 passes through opening 16 in disc 10, through radial slot 18 adjacent the closed end thereof, through opening 18a in disc 11 and thence through opening 16a in disc 10. In this manner the vertical parallel arms 15a and the base portion 15b are formed. Radial portions 15c and base portion 15b are parallel to each other whereas arms 15a are perpendicular to discs 10 and 11, and portions 15c and 15b. The length of vertical arms 15a or the distance between discs 10 and 11 is such as to accommodate the lock of hair to be wound upon said arms 15a. The ends 30 of strip 15 terminate at the peripheral edge of upper disc member 10 at diametrically opposed points.

35 The lock of hair is inserted through slot 18 in lower disc 11 and is then spirally wound around vertical arms 15a, the said arms acting

as a pivot. Portions 17 of upper disc 10 are then bent downwardly, thus encasing and holding the spirally wound lock of hair in the device. Bent portions 17 of disc 10 will not spread back into place but will retain the shape into which they are bent because of wires 13.

It will be noted that the bottom face of lower disc member 11 is always adjacent the scalp while the lock of hair is being wound and after the device is in place.

The construction shown in Figs. 6 and 7 is generally similar to the first above described embodiment, save that in the second embodiment the connecting strip is detachably secured to the upper disc, whereas in the first embodiment, it is fixedly secured to the upper disc member. In other words, the vertical arms of the connecting strip may be extended to accommodate a thicker lock of hair in the device.

The device of the second embodiment comprises an upper disc member 20 and a lower disc member 21 secured to each other by a twistable connecting strip 22. The lower disc member 21 is identical in all respects to lower disc 11 of the first embodiment. Said disc 21 is provided with the radial slot 23 and the opening 23a, which correspond respectively to slot 18 and opening 18a in bottom disc member 11 of the first embodiment.

As shown in Figs. 6 and 7, upper disc member 20 is provided with a plurality of female snap fasteners 24 at its upper face. The bottom face of strip 22 is provided adjacent the ends thereof with a male snap fastener 25, which is adapted to be received by any of the female fastener elements 24. In this manner, vertical arms 22a of connecting strip 22 may be varied in length, in order to accommodate locks of hair of varying thicknesses. The numeral 22b designates the base of connecting strip 22 which extends through and is parallel to bottom disc 21. It will be noted that connecting strip 22 connects disc members 20 and 21 in the same manner as connecting strip 15 connects upper disc 10 and lower disc 11 of the first embodiment. The only substantial difference between the two embodiments is that the device of the second embodiment is adjustable, whereas the device of the first embodiment is not.

Although preferred and practical embodiments of the invention have been described and illustrated, it is obvious that numerous changes and omissions and additions may be made without departing from its spirit.

If the upper disc member is made of aluminum foil or metal foil, it is then unnecessary to reinforce the same with intersecting short lengths of wire or the like.

I claim:

1. A hair curler device comprising a pair of spaced and axially aligned disc members formed of a pliable material, a flexible connecting strip member secured to one of said disc members axially connecting said disc members to each other, one of said disc members having a slot

formed therein adapted to receive a strand of hair to be spirally wound around said connecting strip.

5 2. A hair curler device comprising a top disc member and a bottom disc member spaced from each other and axially aligned, said disc members being formed of a pliable material, a flexible connecting strip member secured to the top disc member and axially connecting said top 10 disc member to the bottom disc member, said bottom disc member having a radial slot formed therein adapted to receive a strand of hair to be spirally wound around said connecting strip.

15 3. A pliable hair curler device comprising a pliable top disc member and a pliable bottom disc member spaced from and axially associated with each other, said disc members being axially aligned and having openings formed therein, a flexible connecting strip member having its end portions secured to the top disc member and axially connecting said disc members to each other, the intermediate portion of said connecting strip member passing through the 20 openings in said disc members to form means around which a strand of hair can be spirally wound.

25 4. A hair curler device according to claim 3, in which the top disc member is provided with pliable reinforcing means whereby the sides of said disc member can be bent downwardly to retain the wound strand of hair between the disc members.

30 5. A hair curling device comprising a top disc member and a bottom disc member formed of pliable material, said disc members being spaced from each other and being axially aligned, the top disc member having a pair of openings formed therein, the bottom disc member having a radial slot and an opening formed therein 35 which are aligned with the openings in said top disc member, a flexible connecting strip member having its ends secured to the top face of said top disc member and axially connecting said disc members to each other, the intermediate portion of said connecting strip member passing through the 40 openings in said disc members to form a pair of vertical arms around which a strand of hair can be spirally wound after being inserted into the device through the radial slot in the bottom disc member.

45 6. A hair curling device according to claim 5, in which the top disc member is provided with pliable reinforcing means whereby the sides of said disc member can be bent downwardly to retain the wound strand of hair between the disc members.

50 7. A hair curling device according to claim 5, in which the connecting strip member is detachably secured to the top disc member, said connecting strip and disc members being provided with adjustable cooperating fastening means whereby the distance between the top and bottom disc members may be varied.

NAOMI G. MORTON.
